UNITED STATES PATENT OFFICE.

GEORGE T. THOMAYER, OF ALBANY, NEW YORK, ASSIGNOR TO FULD AND HATCH
KNITTING COMPANY, A CORPORATION OF NEW YORK.

YARN-DYEING MACHINE.

Application filed September 30, 1922. Serial No. 591,475.

To all whom it may concern:

Be it known that I, GEORGE T. THOMAYER, a citizen of the United States, and a resident of Albany, county of Albany, State of New York, have invented certain new and useful Improvements in Yarn-Dyeing Machines, of which the following is a specification.

The present invention relates to a method of and apparatus for dyeing yarn, and, more particularly, to a method and apparatus for dyeing yarn at intervals or in spots to form a random yarn as the yarn passes from an unwinding to a winding bobbin.

In apparatus heretofore used for this purpose, the yarn has been forcibly pressed against a printing or dyeing surface in such a manner as to frictionally engage and wipe the printing or dyeing surface. This pressure and wiping action, however, tended to scrape off fibres from the yarn as it passed against the pressing or depressing surfaces or eyelets and as it was wiped against the dyeing surface. The lint formed in this manner collected on the yarn and on the dye wiping surface and became saturated with dye and with dust and dirt. A quantity of the lint was continually thereby formed and this lint with the accumulated dust and dirt became attached to the yarn giving the resulting yarn and subsequently the knitted cloth, a dirty, ragged appearance.

An object of the present invention is to provide an apparatus by which yarn may be rapidly dyed at intervals to form a random dyed yarn of clean and pleasing appearance.

Another object of the invention is to provide an apparatus by which yarn is lightly touched on the dyeing means at intervals without pressure or wiping action.

A further object of the invention is to provide an apparatus by which yarn may be dyed in a random fashion while passing to a winding spool or bobbin without the formation of troublesome quantities of lint.

A still further object of the invention is to provide a method of dyeing yarn in a random fashion without the formation of lint and to produce a yarn of clean appearance.

Still further objects of the invention comprise the provision of an improved dye ap-

plying means, an improved randoming means and other improvements in the apparatus and method of dyeing yarn.

With these and other objects in view, the invention comprises the apparatus and method described and set forth in the following specification and claims.

The various features of the invention are illustrated in the accompanying drawings in which:

Fig. 1 is an end view of a part of a winding and dyeing machine embodying a form of the invention.

Fig. 2 is a sectional view taken through a dye applying means and randomer device forming a portion of the apparatus of Fig. 1, the upward throw of the yarn being indicated in dotted lines and the position of the threads when receiving the dye in full lines, both being exaggerated.

Fig. 3 is a top view of a dye container and applying roller or wheel illustrated in Fig. 2.

Fig. 4 is a detail view on an enlarged scale of the dye applying roller, a portion being broken away to illustrate the interior structure of the wheel.

Fig. 5 is a detail view of an absorbing plug for the dye applying wheel illustrated in Fig. 4, and

Fig. 6 is a detail perspective view of the randomer or device for tossing the yarn up from the dyeing surface.

In the present invention, the yarn in passing at a high speed from an unwinding cop to a winding bobbin is permitted at intervals to lightly touch upon a surface covered with a suitable dye. The yarn is so guided over the dye applying surface as to gravitate upon and thus contact lightly, by virtue only of its weight, with the dye applying surface and thus soak up or absorb the dye when hanging loosely between supporting guides on opposite sides of the said dyeing surface. The yarn is thrown lightly upwardly and permitted to fall back to the dye surface by the action of gravity and remain in contact with the dye surface until again thrown upwardly, thus causing the yarn to be dyed for the desired length. This action repeated, gives a succession of dyed spots upon the yarn. A roller or wheel rotating in the same direction as the

passage of the yarn and having its periphery covered or wetted with a dye solution against which the yarn touches or passes tangentially is preferably used as a dyeing surface, there being no positive rubbing or wiping action produced as the yarn falls into contact with the roller.

In the accompanying drawings an embodiment of the invention is illustrated as applied to yarn winding machines of the type shown in the patents to Huse No. 348,561 of September 7, 1886, and Kilbourn No. 619,893 of February 21, 1899, the details of these machines not being described or shown as they are of standard construction and do not form a part of the invention. Referring to the accompanying drawings, the yarn 9 is taken from an unwinding cop 10 and passes through guiding eyelets 12 and through the dyeing apparatus of the present invention to a winding bobbin 14, the winding of the yarn on the bobbin being guided by means of a guiding device 16 of the usual type.

As the yarn passes from the eyelets 12 through the dyeing apparatus it passes over a guide wheel or pulley 18 and over a dye containing tank 20 to eyelets 22 and 24 from which it passes to the guide 16 and bobbin 14. A dye applying wheel or roller 26 is so positioned in the tank 20 that its upper periphery lightly touches the yarn and, as the wheel is rotated, carries a film of dye solution to a position to be absorbed or soaked up by the yarn. It is neither necessary nor desirable that the dye be rubbed off from the wheel onto the yarn and the wheel is therefore preferably rotated in a direction to give its periphery the same direction of movement as the yarn in order to avoid a rubbing action and the consequent formation of lint.

The dyeing of the yarn is interrupted at the desired intervals by means of a randomizing or tossing device 28 positioned between the guide pulley 18 and the dye wheel 26 which successively tosses the passing thread to the position shown in dotted lines in Figs. 1 and 2 as it passes at a high rate of speed over the dye wheel and permits it to fall back into contact with the dye wheel. The randomer is preferably in the form of a solid wheel having grooves or kerfs 30 cut into its periphery to form flat chord surfaces 32 extending diametrically to opposite parts of the periphery. When the surfaces 32 are level with the top of the dye wheel the yarn is permitted to fall and when the ends of this surface are brought upwardly against the yarn the yarn is thrown upwardly. The randomer is preferably rotated in a direction opposite to the rotation of the dye wheel 26.

The dye applying wheel 26 is preferably constructed to provide a surface on which a

film of dye, sufficient to give the yarn the desired color, is carried out of the body of dye liquor and from which the dye may be readily taken up or absorbed. The wheel is preferably formed of a circular plate having pockets at intervals in its circumference in which are placed masses of absorbent material. A suitable wheel is shown in Fig. 4 in which embodiment the wheel is formed of a solid disc of metal having a number of holes 34 bored radially inwardly from the peripheral surface of the disc. These holes are preferably of such a size and depth that they meet toward the center of the disc. Plugs 36 of felt or other fibrous absorptive material are inserted into the holes 34 to act as an absorptive medium, the outer ends of the plugs being substantially even with the peripheral surface of the disc. The plugs 36 may be rectangular strips of felt, as shown in Fig. 5, cut from a piece of the proper thickness. The surface of the dye wheel is thereby formed of alternating sections of felt soaked in dye liquor and smooth sections of metallic surface from which the dye may be readily absorbed and to which the yarn fibres do not tend to adhere. The face of the disc between the holes 34 may be dished in slightly as at 37.

The dye tank is preferably covered and formed of a horizontal section of pipe or tubing in the uppermost surface of which are cut radial slits or openings 38 into which the upper section of the dye wheel surface rotates. With this construction, and the elimination of the formation of lint, there is very little tendency for dirt to be carried into the tank and contaminate the dye liquor.

A number of cops, winding bobbins and dye applying wheels are usually mounted on a single machine, there being a row of units on each side of a machine. A single dye tank may be used for a number of dye wheels and units on one side of the machine, the rotation of the wheels serving to agitate the dye liquor and maintain it in a uniform condition. The dye tank may be supported on the frame of the machine by means of brackets 40. The guide pulleys 18 are supported individually from the tank by means of individual brackets 42. The random or tossing wheels 28 on each side of the machine are preferably supported on and rotated on a common shaft 44, which is, in turn, supported from the tank 20 by means of brackets 46. The shafts 44 and the random wheels may be driven from the driving shaft of the winding bobbins by means of a belt 48 and a pulley 50 mounted on the shaft 44.

The dye wheels 26 are similarly supported on and rotated by a shaft 52 extending through the ends of the dye tanks. The shaft 52 is also driven by means of a pulley

54 mounted on the end outside of the dye tank and driven from the bobbin driving shaft by means of a belt 56.

By means of the above invention the yarn 5 passes over the dye applying wheel in a freely flapping or wave motion, in the lower position of which it absorbs dye from the wheel and in the upper position is left free from dye. The production of lint is reduced to a minimum and a clean appearing, 10 random dyeing of uniform uninjured texture is produced.

Having described the invention what I 15 claim and desire to secure by Letters Patent is:

1. A method of random dyeing yarn by lightly touching the moving yarn in spaced sections with a surface wetted with dye liquor.

20 2. A method of random dyeing yarn by causing moving yarn to swing freely at intervals in contact with a dyeing surface.

3. A method of dyeing yarn by lightly touching moving yarn upon a dyeing surface in spaced sections by intermittently gravitating the yarn thereupon.

4. A method of random dyeing yarn which comprises passing said yarn over and in contact with a surface wetted with dye 30 liquor and throwing said yarn from said surface at intervals.

5. A method of random dyeing yarn which comprises passing said yarn over a surface wetted with dye liquor and permitting said yarn to drop against said surface at successive intervals.

6. A method of random dyeing yarn which comprises passing said yarn continuously over a dye surface, causing said dye 40 surface to travel in the same direction as said yarn forming a film of dye liquor on said surface, and permitting said yarn to drop against said surface at successive intervals.

45 7. A method of random dyeing yarn which comprises maintaining a film of dye liquor on a dyeing surface, passing yarn over said surface and causing said yarn to flap into and out of contact with said film of dye liquor.

8. An apparatus of the kind described which comprises, means for maintaining a film of dye liquor, means for passing yarn over said film and means for permitting 55 said yarn to drop lightly on said film at successive intervals.

9. An apparatus of the kind described which comprises a dye surface, means for maintaining a film of dye liquor on said 60 surface, means for passing yarn lightly over said surface and means for lightly throwing said yarn out of contact with said film at successive intervals.

65 10. An apparatus of the kind described which comprises a rotating surface, means

for maintaining a film of dye liquor on said surface, means for passing yarn in contact with said film and means for throwing said yarn out of contact with said film at successive intervals.

70 11. An apparatus of the kind described which comprises a container for dye liquor, a rotating surface dipping into said dye liquor, means for passing yarn tangentially to the upper periphery of said surface and means for throwing said yarn upwardly from said surface at successive intervals.

75 12. An apparatus of the kind described which comprises, means for unwinding yarn, means for winding yarn, means for guiding said yarn from said unwinding means to said winding means, means for wetting said guided yarn with a dye liquor and means for throwing said yarn out of contact with said wetting means at successive intervals.

80 13. An apparatus of the kind described which comprises means for passing yarn from an unwinding means to a winding means, means for giving said yarn a loosely waving motion and means for wetting said 85 yarn in one direction of its waving motion, by permitting said yarn to fall lightly on a dye liquor surface.

85 14. An apparatus of the kind described which comprises a dye containing tank, guides on opposite sides of said tank, means for passing yarn through said guides, a dye wheel rotating in said tank in position to be wetted with dye liquor and to support yarn passing through said guides, and a tossing means between said guides having rotating surfaces adapted to throw said yarn upwardly from said dye wheel.

90 15. An apparatus of the kind described which comprises a series of unwinding means and a series of winding bobbins, a tank of dye liquor between said unwinding and winding means, a series of dye applying wheels in said tanks, means for guiding yarn from said unwinding means in light contact with the upper surface of said 100 wheels, a shaft extending lengthwise of said tank and rotating means on said shaft for tossing said yarn upwardly from said dye applying wheels at successive intervals.

110 16. An apparatus of the kind described which comprises, a tank for dye liquor, a rotating surface dipping into said dye liquor, means for passing yarn over said surface in the same direction of movement as said surface, and means for giving said yarn a free, waving upward and downward movement into and out of contact with said rotating surface.

120 In witness whereof I have hereunto set 125 my hand at Albany, county of Albany, State of New York, this 21st day of September, 1922.

GEORGE T. THOMAYER.
